HAND SANDER

James A. Westerfield, 1215 Moreland Ave.,
Owensboro, Ky.

Filed Feb. 23, 1960, Ser. No. 10,269
2 Claims. (Cl. 51—170)

This invention relates to a portable device for sanding various surfaces, and is intended to be employed for jobs suitable for belt sanding. The invention is power driven, preferably by an ordinary small drill electric motor, such for example as having the capacity up to a quarter-inch drill.

A primary object of the invention is to provide a sander of the above indicated nature wherein the belt may be readily applied and removed, with an easily adjusting means for tensioning the belt, and also having means for aligning the belt.

In many of these devices wherein a sanding belt is employed, difficulties are encountered in preventing the replaceable belt from running off the pulley, and also in not having sufficient tensioning means for driving the belt under heavy sanding operations.

The primary object of the invention is to incorporate such a device in a light mechanism which has a minimum number of parts; easily accessible; and positive and long lived.

These and many other objects and advantages of the invention will become apparent in the following description of one particular form of the invention as illustrated in the accompanying drawing, in which

FIG. 1 is a view in top plan of a structure including the invention;

FIG. 2 is a view in left hand side elevation with a portion of the wall of a bracket supporting a belt pressure shoe broken away; and

FIG. 3 is a view in bottom plan, with portions broken away to disclose the driving shaft.

A body 10 is provided to rotatably carry a driving shaft 11 transversely therethrough near one end of the body, and an idler shaft 12 is fixed in a holder which in turn is carried by the other end thereof. Both of these shafts 11 and 12 extend transversely across the body 10 to be in parallel alignment one with the other.

A pulley 13 is fixed on the shaft 11, herein shown as on the left hand side of the body 10. A pulley 14 of substantially the same diameter as that of the pulley 13 is revolvably carried on the shaft 12.

An endless belt of sand paper 15 is placed over and around these two pulleys, 13 and 14, as indicated in FIG. 2. This sand paper may be of any suitable backing such as paper or cloth, and be coated with the desirable abrasive on its outer surface removed from the surfaces of the pulleys 13 and 14.

The holder above referred to is identified generally by the numeral 16 and is generally T-shaped. The holder 16 grips the shaft 12 at the wide end of the holder as indicated in FIG. 3, whereinto bands 17 and 18 are turned around to encircle the shaft 12. The under side of the body 10 is cut away as at 19, FIG. 2, to provide clearance for the shaft 12 thereunder. The holder 16 has a down-turned leg 20 with a threaded member 21 fixed thereto. A screw-threaded shaft 22 screw-threadedly passes through the leg 20 and the member 21, and is an extension from an operating handle 23 which abuts by one end a bracket 24 fixed to and extending downwardly from the under side of the body 10 and the cutaway portion 19. The shaft 22 revolvably extends through the bracket 24, so that the holder 16 may be shifted toward and away from the bracket 24 by turning the member 23 accordingly.

2

The holder 16 extends along under the body 10 to terminate in a loop 25 formed by bending a portion of the body 16 from its major surface around and in spaced relation back thereunder. A belt aligning handle 26 is provided with a screw-threaded shaft 27 passing through the loop 25 with the end of the handle 26 in abutment against a side of the loop upper and lower portions 28 and 29 respectively. The shaft 27 screw-threadedly passes through a bracket 30 fixed to the underside of the body 10, preferably in a recess thereunder, and may in addition pass through a screw-threaded member 31 fixed to the side of the bracket so as to produce an increased length of a threaded portion of the bracket 30 over and above the thickness of the bracket itself.

By rotating the handle 26, the holder 16 may be rocked, and in turn the pulley 14 rocked accordingly since it is on the extension the shaft 12 beyond the body 10. It takes but very little rocking of the holder 16 to align the belt 15 on the two pulleys 13 and 14 so as to keep the belt running true without tending to run off the pulleys. In the rocking of the holder 16, the shaft 22 may rock accordingly since the shaft 22 loosely passes through the bracket 24. That is, the looseness of the shaft 22 in the bracket 24 is only that which will permit this rocking without permitting any undue longitudinal travel of the shaft 12 relative to the body 10. Thus by turning the handle 26 in either possible direction, the holder 16 may be rocked accordingly to provide the necessary alignment of the two pulleys for retaining the belt 15 thereon.

A suitable guard or cover 32 is mounted on the body 10 to overhang therefrom in spaced relation above the upper flight of the belt 15 as a safety device. The sander is supported and guided by a handle 33 which extends upwardly from the topside of the body 10. A drill (not illustrated) may through its chuck engage the extension of the shaft 11 which appears on the right hand side of the device as illustrated.

In operation, the sander is gripped, normally by having the left hand grasp the handle 33 and the right hand grasp the drill body which is attached to the shaft 11. In this manner, the device may be guided over the surface to be sanded, with ease and safety. When the belt 15 becomes worn as to its abrasive characteristics, operating member 23 may be turned to release the tension on the belt 15 so that the old one may be slid off and a new one replaced, and then tension applied again by turning the member 23 in the opposite direction, the alignment of the belt over the pulleys being of course again adjusted by the member 26.

A pressure shoe 35 comprising a flat plate is spaced under the body closely over the lower belt flight 15a by a supporting bracket 36 fixed by its upper end to the body 10.

While I have herein shown and described my invention in the one particular form, it is obvious that structural changes may be made, such as making the device left handed as well as right handed as described, and other changes in the structure all without departing from the spirit of the invention. I therefore do not desire to be limited to that precise form beyond the limitations which may be imposed by the following claims.

I claim:

1. A portable belt sander comprising a body; a driving shaft rotatably carried across one end portion of the body; said shaft having driving and driven ends extending from sides of the body; a belt drive pulley fixed to the driven end of said shaft out side of the body; an idler shaft; a member extending downwardly from said body at its end portion opposite from said one end portion; a screw shaft revolvably and laterally rockably carried by said member; a horizontally disposed holder plate having bear-

ing means at one end through which said idler shaft is revolvably carried to have a shaft portion extend laterally from the holder and beyond the same body side as does said drive pulley; an idler pulley on said idler shaft outside of the body; said holder having a member extending therefrom adjacent said idler shaft and through which member said screw shaft screw-threadedly passes; said holder extending along under said body from said idler shaft to a free end; a second screw shaft; a member carried by said body and screw-threadedly engaged by said second screw shaft; an abutment on said last shaft in the path of said plate end; and an endless sanding belt extending around said pulleys; travel of said holder being had to space said idler shaft toward and away from the driving shaft by rotation of said first screw shaft, and

5
10
15

rocking of the idler shaft being had by rotation of said second screw shaft; said belt, through pull by said first screw shaft on said holder, maintaining the holder rocked by its said free end against said second screw shaft.

2. The structure of claim 1 in which said holder free end loops around said second screw shaft and said abutment thereon bears against sides of the loop, said loop permitting said holder free end to travel laterally of said second screw shaft.
